US00D611218S

(12) **United States Design Patent**
Connor et al.

(10) **Patent No.:** US D611,218 S
(45) **Date of Patent:** ** *Mar. 2, 2010

(54) **LID**

5,150,806 A 9/1992 Glomski

(75) Inventors: **Pat Connor**, Kitchener (CA); **Paul Goyette**, Penetanguishene (CA); **Gordon Bennett**, Midland (CA)

(Continued)

(73) Assignee: **Jake's Holding Corporation**, Kitchener, Ontario

CA 1268153 A 4/1990

(**) Term: **14 Years**

(Continued)

(21) Appl. No.: **29/333,207**

The ornamental design for a lid, as shown and described.

DESCRIPTION

FIG. 1 is a rear perspective view of a lid, exemplary of an embodiment of the design;

FIG. 2 is an underside perspective view of the lid of FIG. 1; FIG. 3 is a right-hand side elevational view of the lid of FIG. 1;

FIG. 4 is a rear elevational view of the lid of FIG. 1;

FIG. 5 is a left-hand side elevational view of the lid of FIG. 1;

FIG. 6 is a front elevational view of the lid of FIG. 1;

FIG. 7 is a top plan view of the lid of FIG. 1; and,

FIG. 8 is a bottom plan view of the lid of FIG. 1.
